UNITED STATES PATENT OFFICE

169,670

CAPE

Matilda E. Homan, Los Angeles, Calif.

Application December 17, 1952, Serial No. 22,744

Term of patent 7 years

(Cl. D3—3)

To all whom it may concern:

Be it known that I, Matilda E. Homan, a citizen of Great Britain, residing at 8964 Shoreham Drive, Los Angeles, Los Angeles County, State of California, have invented a new, original, and ornamental Design for a Cape, of which the following is a specification, reference being had to the accompanying drawing, forming a part hereof.

Fig. 1 is a plan view of the cape of my design in extended position;

Fig. 2 is a front elevational view of the cape shown in Fig. 1 doubled over on itself and in wearing position, and

Fig. 3 is a rear view of Fig. 2.

I claim:

The ornamental design for a cape, as shown.

MATILDA E. HOMAN.
